ENAMELED METAL WALL CONSTRUCTION

William Hogenson, Hinsdale, Ill., assignor to Chicago Vitreous Enamel Product Co., Cicero, Ill., a corporation of Illinois

Application August 30, 1934, Serial No. 742,029

15 Claims. (Cl. 189—85)

This invention relates to enameled metal wall construction of a type particularly suited for use in the erection or remodeling of buildings, homes, filling stations and the like.

In constructing external or internal walls of porcelain enameled metal, a number of problems are always present. It is, of course, essential to devise a method whereby the enameled metal plates or sections can be securely held in place without danger of becoming loose due to expansion or contraction or buckling of the plates. It is also necessary that the joints between the porcelain enameled metal plates or sections be water tight to prevent the seepage of water or moisture inwardly. There is also the problem of so insulating the enamel metal wall structure as to make it possible to keep the interior of the building comfortable notwithstanding extremes of atmospheric conditions. This includes providing means for preventing the collection of moisture on the inside of the enameled metal plates or sections under conditions that would cause "sweating" of the metal. As a final consideration, the joints between the enameled metal sections must be so concealed or ornamented as to create a pleasing appearance to the wall or building.

Numerous types of constructions have been devised looking toward a solution of these various problems. The present invention has for its object to provide a wall construction of a relatively simple and inexpensive type that is peculiarly adapted for use in the erection of new buildings or the remodeling of existing frame houses and similar structures.

It is a further object of this invention to provide an enameled metal wall construction wherein the enameled metal panels are individually mounted on rigid insulation board and are secured in position in the wall structure in spaced relation from each other to compensate for expansion and contraction of the panels and to permit easy replacement of the panels from the outside of the wall without disturbing any other panel or part of the supporting structure.

It is a further important object of this invention to provide an enameled metal wall construction that does not require highly skilled labor in its erection and wherein inexpensive and ordinary building materials may be used rather than the more or less special types of keying devices and the like that have heretofore been proposed.

It is a further important object of this invention to provide a construction that will insure water tight joints between the enameled metal

plates or sections and the underlying structural elements of the wall construction.

It is a further important object of this invention to provide a type of enameled metal wall construction that may be erected "dry", that is, without the use of aqueous cement, plasters, and the like for filling in joints. 5

It is a further important object of this invention to provide a permanent, water tight and heat insulated wall construction using porcelain 10 enameled metal as the external or internal surface material.

Other and further important objects of this invention will become apparent from the following description, the drawing and appended 15 claims.

On the drawing:

Figure 1 is a fragmentary elevational view of a portion of enameled metal wall construction embodying the principles of my invention, with parts 20 broken away and in section.

Figure 2 is an enlarged sectional view taken substantially on the line II—II of Fig. 1.

Figure 3 is an enlarged sectional view showing a modified type of joint construction. 25

Figure 4 is a sectional view showing a further modification of my invention.

Figure 5 is a broken elevational view of the metal trim shown in Fig. 4.

Figure 6 is a fragmentary enlarged bottom plan 30 view of the metal trim shown in Figs. 4 and 5.

As shown on the drawing:

The reference numeral 10 indicates a wall which may represent new construction or a portion of an existing frame structure that is to be 35 remodeled to provide an external surface of porcelain enameled metal. Said wall structure 10 includes vertically extending studding 11 and horizontally extending stringers 12 joined together in the usual way. A baseboard 13, floor-board or the like, extends around the base of the wall structure. 40

As shown in Figs. 1 and 2, each of the props or studs 11 is provided with a narrower strip of 45 wood, or furring strip 13, that extends longitudinally of the prop or stud and is initially secured thereto by means of nails or the like, with an underlying layer 14 of a mastic cement or adhesive. As shown, the furring strips 13 are about a third or a quarter of the width of the studs 11 and are secured to the broader, outward faces of 50 said studs 11 centrally of such faces. Instead of separately nailing furring strips to the studding, a specially formed studding or stringer may be 55

made with an integral strip on one or both faces, as indicated at 50 (Fig. 1).

Wall boards 15 of suitable, rigid insulation material, are positioned against the exterior faces 5 of the studs 11 with their ends in abutting relation to the strips 13 and with a layer of plastic cement or adhesive between the adjacent surfaces, as at 16 and 17. The boards 15 are preferably of such thickness that their external surfaces 10 are flush with the external faces of the strips 13. It will be understood that the thicknesses of the adhesive layers 14, 16 and 17 are somewhat exaggerated in the drawing for purposes of illustration and that in reality these 15 layers are relatively thinner than indicated.

Plates or sections 18 of porcelain enameled metal are secured to the panels of insulation board 15 by means of a layer 19 of suitable cement. Preferably the plates 18 and insulation board 15 are pre-fabricated, ahead of the actual erection job, so that each enameled metal plate 18 has a panel of wall board as a backing. The assembled panels are handled as units and properly positioned with respect to the studding and 20 stringers. In each assembled panel, the marginal portions 20 of the enameled metal plates overhang, or extend beyond the backing of insulation board so as to overlie the furring strips 13 when the panel is positioned in place.

30 Said enameled metal sections 18 may be of any convenient size, say, from 2 to 8 feet in length and from 6 to 24 inches in width. The panels are arranged in horizontal rows with the vertically extending joints preferably staggered. 35 In securing the panels in place, with the adjacent outer edges 20 overlapping the exterior faces of the strips 13, each plate 18 is slightly spaced from the adjacent plates to allow for expansion and contraction and also to permit fastening of 40 the trim in place, as will presently be described. The joints between said edges 20 and the face of said strips 13 are caulked, as at 21.

The porcelain enameled plates 18 are provided with holes along their edges 20 to permit nails 45 22 to be driven therethrough into the strips 13, thereby securing said plates 18 in place. The nails 22 are ordinarily of such length that they do not extend into the props or studs 11, but longer nails may be used if desired.

50 Metal strips 23, which may suitably be of stainless steel, chromium plated steel or the like, serve as trim for concealing the heads of the nails 22 and the joints between the adjacent enameled metal plates 18. Said metal strips 23 are provided with apertures at spaced intervals to permit them to be secured in place, as by means of screws 24, that are threaded through the wooden strips 13 into the props or studs 11. Each of the strips 23 is provided with edge flanges 25 that 55 are adapted to abut against the surfaces of the adjacent enameled metal plates 18 to provide a comparatively tight joint. The resiliency of the metal strips 23 aids in insuring tight joints between the strips and the adjoining enameled 60 metal plates 18.

65 It will be understood that similar joints are provided between the insulation boards, the porcelain enameled metal plates, and the horizontal stringers 12. In each case, a continuous layer of plastic cement, adhesive or the like, is preferably applied between all of the adjoining or abutting surfaces of the members making up the joint, so that the joint will be entirely waterproof. Suitable types of plastic cements or adhesives 70 are available for this purpose. They are 75

preferably of an oil or asphalt type rather than of a water type, so as to avoid the necessity of being dried out.

The joint structure illustrated in Fig. 3 comprises a pair of channel shaped structural elements 30 and 31 arranged with their web portions in back to back relationship. The channel members 30 and 31 may be of metal, preferably rolled steel, and serve as structural elements of the building in place of the wooden studding and 10 stringers previously described. In building up of joints about the channel members 30 and 31, these members are first provided with wooden filler strips 32 and 33, suitably secured in place. The remaining joint structure is substantially as 15 above described. Wooden strips 13a are cemented or otherwise secured along the broad faces of the filler strips 32, or formed integral therewith, and insulation board 15a faced with porcelain enameled metal sections 18a are secured in place 20 by means of nails 22a, trimming strips 23a and screws 24a.

In the construction illustrated in Fig. 3, both the internal and external wall surfaces may be built up and joined to the channel members 30 and 31 in the same way. The space 51 between the insulation boards may be filled with loose or blanket insulation material, if desired.

In Figs. 4 to 6 inclusive, there is shown a similar type of joint construction but with a different form of trim. Strips 35 of trimming material are formed by folding flat strips of metal to provide a continuous, flat outer surface 36 and an inner slotted surface made up of the opposing flanges 37 and 38. Said flanges 37 and 35 are spaced apart for portions of their length to provide slots 39 for receiving the shanks of the nails 40 and for other portions of their length are provided with enlarged slots 41 capable of permitting the passage therethrough of the heads of 40 said nails 40.

In the construction shown in Figs. 4 to 6 inclusive, nails similar to the nails 22 may be used or not, but it is sufficient to use nails 40 and the trimming strips 35 for securing the enameled metal plates 18b in position. In assembling the joint, the wooden strips 13b are initially secured to the studs, props or the like 11b by means of adhesive or other securing means, or may be formed integral with the studs. The pre-fabricated panels comprising the enameled metal plates 18b and the insulation board 15b backing are then applied with the margins of the metal plates overlapping the wooden strips 13b but spaced to provide for the insertion of the nails 40. Said 50 nails 40 are then driven part way into the strips 13b and the trimming strips 35 inserted over the heads of said nails 40 and moved along until said nail heads 40 are enclosed within said strips with the shanks of the nails extending through the 55 narrower slot portions 39. With the trimming strips in this position, the nails 40 are pounded in the rest of the way, using a wooden strip or other protecting means to prevent marring the trimming strips 35. Instead of driving the nails 60 40 in on the job, the nails may be partially driven ahead of time, by machinery or otherwise, into special studding and stringers having the furring strip integrally formed therewith as indicated at 65 50 (Fig. 1).

When completely assembled, the trimming strips 35 overlie and enclose the heads of the nails 40 to be held in place thereby and conceal the gap between the edges of the enameled metal plates 18b. Like the other joints described, a 70 75

joint of this type is entirely waterproof due to the use of a waterproof caulking material or cement between the adjoining and abutting surfaces of the elements making up the joint.

5 It will be appreciated that the type of joint illustrated herein is particularly suited for use in the remodeling of existing wooden frame houses, buildings and the like, since the regular studding and stringers may be adapted to use 10 by the simple expediency of securing narrower wooden strips, such as the furring strips 13, to their exterior faces. Another advantage of my type of construction is that it eliminates the necessity of using hydraulic setting materials, such 15 as mortar, plaster or the like. All of the joints are pointed or caulked with an elastic or mastic cement that does not introduce water into the joint.

An important feature of my construction is 20 that the enameled metal plates or panels are separately and independently mounted, so that successive panels do not have to sustain the weight of each other or of other panels. Each panel sustains only its own weight and is separately secured in place and may be readily replaced if necessary. Furthermore, since successive panels do not contact each other, there is no likelihood of the panels buckling or springing 25 from expansion or contraction.

30 I am aware that many changes may be made and numerous details of construction may be varied through a wide range without departing from the principles of this invention, and I, therefore, do not purpose limiting the patent granted 35 hereon otherwise than necessitated by the prior art.

I claim as my invention:

1. A wall structure comprising structural members, wooden strips positioned thereagainst, insulation board positioned against said members and abutting said strips, metal sections overlying said insulation board with their edges extending along said strips, trim concealing said edges and means securing said trim to said strips.

45 2. A wall structure comprising structural members, wooden strips positioned thereagainst, insulation board positioned against said members and abutting said strips, porcelain enameled metal sections overlying said insulation board with their edges extending along said strips, trim concealing said edges and means securing said trim to said strips, a waterproof adhesive layer sealing the joints between said sections and said strips, between said insulation board and said strips and between said insulation board and said structural 50 members.

55 3. A wall structure comprising structural members, wooden strips positioned thereagainst, insulation board positioned against said members and abutting said strips, porcelain enameled metal sections overlying said insulation board with their edges extending along said strips, means securing said metal sections to said strips, trim concealing said edges and means securing said trim to said strips and said strips to said structural members.

60 4. A wall structure comprising wooden studding, furring strips of lesser width extending longitudinally of said studding, insulation board positioned against said studding and abutting said furring strips, porcelain enameled metal plates overlying said insulation board and secured to said furring strips, metal strips concealing the joints between said metal plates and means extending through said metal strips and said furring strips into said studding to secure said strips in place.

75 5. A wall structure comprising wooden stud-

ding, furring strips extending along said studding, insulation board adhesively secured to said studding and to said strips in abutting relation to said strips, enameled metal sections adhesively secured to said insulation board with the edges of said sections extending along said strips and trim overlying said edges.

5 6. A wall structure comprising wooden studding, furring strips on said studding, insulation board adhesively secured to said studding and to said strips in abutting relation to said strips, enameled metal sections adhesively secured to said insulation board with the edges of said sections extending along said strips, trim overlying said edges and means extending through said trim into said strips to secure said trim and sections in place.

10 7. A wall structure comprising structural members, strips secured thereto, insulation board secured to said structural members and to said strips with the outer surfaces of said insulation board and of said strips flush with each other, enameled metal sections adhesively secured to said board with their edges extending along said strips and means securing said sections to said 15 strips.

20 8. A wall structure comprising structural members, strips secured thereto, insulation board secured to said structural members and to said strips with the outer surfaces of said insulation 30 board and of said strips flush with each other, enameled metal sections adhesively secured to said board with their edges extending along said strips, means securing said sections to said strips, metal trim overlying said edges and means securing said trim and said strips to said structural members.

35 9. A wall structure comprising wooden structural members, wooden strips secured thereto, insulation board secured to said structural members and to said strips with the outer surfaces of said insulation board and of said strips flush with each other, enameled metal sections adhesively secured to said board with their edges extending along said strips and nails securing said 40 sections to said strips.

45 10. A wall structure comprising wooden structural members, wooden strips secured thereto, insulation board secured to said structural members and to said strips with the outer surfaces of said insulation board and of said strips flush with each other, enameled metal sections adhesively secured to said board with their edges extending along said strips and means securing said sections to said strips.

50 11. A wall structure comprising channel shaped metal structural members, wooden fillers for said members, furring strips secured to said fillers, insulation board secured to said fillers and to said strips, enameled metal sections overlying said board with their edges extending along said strips, nails securing said sections to said strips and trim concealing said nails and the joints between said sections.

55 12. A wall structure comprising structural members, relatively narrow wooden strips extending along the faces thereof, panels of insulation board abutting against said members and strips and flush with the outer faces of said strips, metal sections overlying said panels with their edges extending along said strips, there being a continuous waterproofing layer extending between all adjacent faces of said members, strips, panels, and metal sections, and means securing said metal sections of said strips.

13. A wall structure comprising structural members, relatively narrow wooden strips extending along the faces thereof, panels of insulation board abutting against said members and strips and flush with the outer faces of said strips, metal sections overlying said panels with their edges extending along said strips, there being a continuous waterproofing layer extending between all adjacent faces of said members, strips, panels, and metal sections, means securing said metal sections to said strips, and trim overlying said edges and secured to said structural members.

14. A wall structure comprising wooden structural members, relatively narrow wooden strips extending along the faces thereof, panels of insulation board abutting against said members and strips and flush with the outer faces of said strips, a porcelain enameled metal plate adhesively secured to each panel and overlying the panel with

its edges extending therebeyond, there being a continuous waterproofing layer extending between all adjacent faces of said members, strips, boards, and metal sections, flat headed nails extending into said strips between said edges and a flanged metal trim having a slotted inner face for receiving the heads of said nails to be secured in place by said nails.

15. In a wall structure including structural members with wooden strips extending therealong and projecting therefrom, laminated panels having an outer lamination of metal extending beyond the edges of the underlying lamination to overlie said wooden strips, the metal edges of adjacent panels being spaced apart, trim overlying said spaced apart edges and securing means extending from said trim between said edges and into said strips.

WILLIAM HOGENSON.
